UNITED STATES PATENT OFFICE

CHARLES D. FIVEASH, OF PORTLAND, OREGON

ATTACHMENT FOR AUTOMATIC TELEPHONE DIALS

Application filed November 20, 1929, Serial No. 408,570. Renewed August 8, 1932.

My device is intended for being placed over the dial of an automatic telephone. The attachment is adapted for being detachably mounted upon the dial.

5. The primary object of the attachment is to provide means for indicating in color the number of the telephone desired to be made prominent and other indicia brought before the user of the telephone and in this manner
10. facilitate the dialing of the number indicated and to display whatever indicia are desired to be displayed.

The invention in its preferred embodiment consists of a body element having openings disposed therethrough that are in registerable alignment with the openings disposed within a standard automatic telephone dial. Simple means are provided for attaching the body element to the dial of the automatic

20. telephone.

The invention consists of a one-piece body element having its peripheral edge adapted for engagement with the peripheral edge of the automatic telephone dial and having a raised surface upon which delineated subjects may be printed, embossed, or otherwise placed thereupon. The rim is adapted for being sprung sufficiently to permit its engagement with the rim of the automatic telephone

30. dial.

A further object of my invention consists in providing a simple attachment for an automatic telephone dial that may be made to carry advertising matter, or other instructional data relating to the telephone.

A still further object of my invention consists in providing an attachment that may be detachably attached about the rim of the telephone dial and that may be utilized for practical, instructional, or educational purposes.

With these and incidental objects in view, the invention consists in certain novel features of construction and combination of parts, the essential elements of which are set forth in the appended claims, and a preferred

form of embodiment of which is hereinafter shown with reference to the drawing which accompanies and forms a part of this specification.

In the drawing:

Fig. 1 is a side elevation of an automatic telephone illustrating one of my new and improved attachments in place upon the dial of the telephone.

Fig. 2 is a top, plan view of the dial illustrating one of my new and improved devices in place thereupon.

Fig. 3 is a cross section view taken on line 3—3 of Fig. 2 looking in the direction indicated.

Fig. 4 is an inverted, plan view of the body element.

Like reference characters refer to like parts throughout the several views.

1 is the dial of an automatic telephone. 2. The stop 3 is disposed upon the body of the standard telephone unit 4. My new and improved attachment consists of a one piece body element 5. A raised section 6 is provided centrally within the body element. A plurality of spaced holes 7 are provided within the body element which are made for being placed in registerable alignment with the openings disposed within the dial of the automatic telephone. An outer rim 8 that is

70. curled inwardly is disposed about the outer periphery of the body element and is adapted for being sprung over the rim of the dial 1 as illustrated at 9 in Fig. 3. The curl should be sufficient only to maintain the attachment upon the dial when forced thereupon. Delineations 10 are placed centrally of the raised portion 6 for instructional and advertising purposes. Further delineations may be placed between the openings 7 and the stop 3 as illustrated at 12.

Assuming that the telephone number of the advertiser delineated upon the raised central portion of the attachment is AT2410, in order to facilitate the dialing of the ad-

vertiser's number AT2410, the letter A would preferably be printed in one of the primary colors as red and the surface of the body of my attachment adjacent the letter A 5 would preferably be red. The letter T may be printed in another of the primary colors, as blue, and the body of the device adjacent the letter T would preferably be printed in blue. The numeral 2, being in the same space, 10 or opening, as the letter A, would be represented in the same color as the letter A, namely red. The numeral 4 would be printed in another of the primary colors, as green and the body of the device adjacent the opening 15 carrying number 4 would be printed in green. The numeral 1 would be printed in a color that would be delineated upon the body of the device adjacent the opening 1 and the numeral 0 would be printed in a 20 designated color and the body of the device adjacent the opening through which the numeral 0 appears would be printed in the same color.

This arrangement greatly facilitates the 25 dialing of the advertiser's number and at the same time affords novelty to the construction itself.

While the form of mechanism herein 30 shown and described is admirably adapted to fulfill the objects primarily stated, it is to be understood that it is not intended to confine the invention to the one form of embodiment herein shown and described, as it is susceptible of embodiment in various 35 forms, all coming within the scope of the claims which follow.

What I claim is:

1. In a device of the class described, the 40 combination with the dial of an automatic telephone, of a body element detachably attachable to the dial of the telephone, said body element comprising a peripheral rim provided with finger holes and a raised section disposed centrally of the rim and having 45 the designation of a predetermined station number marked thereon, each character of said designation having a color to distinguish it from unlike characters, and said rim having areas around the finger holes 50 which are normally positioned over the respective characters on the dial, said areas having the same colors as the corresponding characters in said designation.

2. In a device of the class described, the 55 combination with the dial of an automatic telephone, of a body element, said body element comprising a peripheral rim provided with finger holes and a raised section disposed centrally of the rim and having designation of a predetermined station number 60 marked thereon, each character of said designation having a distinguishing color and said rim having areas around the finger holes which have the same colors as the corresponding characters in said designation.

3. In a device of the class described, the combination with a telephone dial, of a body element disposed about the upper portion of the dial and shaped to the contour thereof, comprising a peripheral rim provided with 70 finger holes and a raised section disposed centrally of the rim and having the designation of a predetermined station number marked thereon, the characters in said designation being marked to distinguish them 75 from unlike characters and the areas around the finger holes being correspondingly marked.

CHARLES D. FIVEASH.
